(57) **CLAIM**

The ornamental design for a paddle for water sports, as shown and described.

DESCRIPTION

FIG. 1 is a right front perspective view of a paddle for water sports showing my new design;

FIG. 2 is a top plan view thereof;

FIG. 3 is a bottom plan view thereof;

FIG. 4 is a left side elevational view, the right side elevational view being a mirror image thereof;

FIG. 5 is a rear elevational view thereof;

FIG. 6 is a front elevational view thereof; and,

FIG. 7 is an enlargement of the left blade shown in FIG. 4.

FIGS. 1 and 4 through 6 have been shown with symbolic breaks in length, wherein the appearance of any portion between the break lines forms no part of the claimed design.
